Attorney, Agent, or Firm—Robert D. Flynn

[57] CLAIM

The ornamental design for a handle for a percussion tool or the like, as shown.

DESCRIPTION

FIG. 1 is a plan view of a handle showing my new design;

FIG. 2 is a bottom view of the handle of FIG. 1;

FIG. 3 is a rear view of the handle of FIG. 1, taken from the top in FIG. 1;

FIG. 4 is a front view of the handle as seen in FIG. 2, taken from the bottom in FIG. 2;

FIG. 5 is an end view of the handle, taken from the left in FIG. 1;

FIG. 6 is an end view of the handle, taken from the right in FIG. 1;

FIG. 7 is a perspective view taken from the right, above and to the rear of the handle of FIG. 1; and

FIG. 8 is a perspective view taken from the left and beneath the handle of FIG. 1.
